Inventor:

Daniel Hughes

UNITED STATES PATENT OFFICE.

DANIEL HUGHES, OF ROCHESTER, NEW YORK.

IMPROVEMENT IN HOOP-LOCKS.

Specification forming part of Letters Patent No. 26,435, dated December 13, 1859.

To all whom it may concern:

Be it known that I, DANIEL HUGHES, of Rochester, in the county of Monroe and State of New York, have invented a new and Improved Hoop-Lock for Securing together the Ends of Metal Hoops on Bales; and I do hereby declare that the following is a full, clear, and exact description of the same, reference being had to the annexed drawings, making a part of this specification, in which—

Figure 1 is a section of my invention, taken in the line $x x$, Fig. 3. Fig. 2 is a section of the same, taken in the line $y y$, Fig. 3; Fig. 3, an outer or external view of the same.

Similar letters of reference indicate corresponding parts in the several figures.

This invention consists in placing within a metal case or box, through which the ends of the hoop to be connected or secured together pass, a clamp or jaw, so hung and arranged within the case or box as to permit the ends of the hoop, when the latter is around the bale, to be shoved one over the other through the case or box in order that the hoop may be snugly adjusted on the bale, and, when the ends of the hoop are slightly drawn back under the expansion of the compressed bale, cause the jaw to bind firmly on the ends of the hoops, so that the latter will be firmly secured in the case or box, and consequently locked or connected together.

The invention is more especially designed to be applied to the hoops of cotton-bales; but it may be applied to all metal bale-hoops.

To enable those skilled in the art to fully understand and construct my invention, I will proceed to describe it.

A represents a case or box, which may be of cast metal and of trilateral prismatic form, as shown clearly in Fig. 2. This case or box has a slot, a , made in two opposite sides of it adjoining its inner side, b , said slots being of sufficient dimensions to allow the ends $c c$ of the hoop to pass freely through the box, one end being lapped over the other, as shown clearly in Fig. 2.

Within the case or box A a clamp or jaw, B, is placed. This clamp or jaw is simply a metal plate or bar having a journal, d , at each side of it, which journals are fitted in recesses $e e$ in the inner surfaces of the ends of the case or box A, as shown clearly in Fig. 1. The inner edge of this clamp or jaw is corrugated,

and it is somewhat eccentric with its journals $d d$, one side of the clamp or jaw being longer than the other, as shown clearly in Fig. 2.

The device is applied as follows: The hoops, any proper number being used, are adjusted around the bale as usual, and when the bale is fully compressed, or as much so as is desired, the ends $c c$ of the hoops are passed through the boxes A, the hoops being adjusted or drawn snugly around the bale. The pressure on the bale is then relaxed and its expansion will draw the ends of the hoop slightly outward in the direction indicated by the arrows, and this movement will cause the clamp or jaw B to bind on the outermost end, c , of the hoop, and bind both ends firmly against the inner side, b , of the box, the stronger the draw the greater the pressure of the clamp or jaw, which will consequently secure firmly the ends of the hoop in the box and connect them together.

It will be seen from the above description that a bale, the hoops of which have their ends secured by my invention, may be compressed and the ends of the hoops will be shoved along under the pressure and secured at the proper point as soon as the pressure on the bale ceases, it being understood that the ends $c c$ may be shoved in the direction indicated by arrow 2 without any resistance from the clamp or jaw, the latter acting only when the ends c are moved in the opposite direction, as indicated by arrow 1. The edge of the clamp or jaw B is made slightly concentric in order to compensate for any variation in the position of the clamp or jaw within the case or box, for if the edge were concentric a slight variation in position might permit the ends of the hoops to draw out from the box.

The clamps or jaws B are placed in the molds in which the cases A are cast, so that the latter are cast around the former.

Having thus described my invention, what I claim as new, and desire to secure by Letters Patent, is—

The case or box A, having slots $a a$ in two opposite sides, and provided with a clamp or jaw B, arranged substantially as and for the purpose set forth.

DANIEL HUGHES.
